UNITED STATES PATENT OFFICE.

OMAR A. ROGERS, OF WEST UNION, IOWA, ASSIGNOR OF ONE-HALF TO
GEORGE H. MOTT, OF FAYETTE COUNTY, IOWA.

DUPLEX STAY FOR BUCKSAWS.

SPECIFICATION forming part of Letters Patent No. 599,795, dated March 1, 1898.

Application filed October 19, 1897. Serial No. 655,749. (No model.)

To all whom it may concern:

Be it known that I, OMAR A. ROGERS, a citizen of the United States, residing at West Union, in the county of Fayette and State of Iowa, have invented new and useful Duplex Stays for Bucksaws, of which the following is a specification.

The object of this invention is to provide an improved bucksaw-frame that is simple in construction and strong and durable and in which all of the movement between the bars and braces of the frame incident to the tightening and loosening of the saw is had through a hinge, so that there is no movement of the tenoned joints of the parts.

This invention consists in the combination, with a bucksaw-frame, of two braces, the meeting ends of which are connected, and a hinge, one end of which is connected with the meeting ends of the braces and the opposite end fixed to a portion of the frame, so that a pivotal connection is had between the braces and one side of the frame, as herein-after more fully set forth, pointed out in my claim, and illustrated in the accompanying drawings, in which—

Figure 1 shows a side elevation of the buck-saw having my improvement applied thereon. Fig. 2 shows a perspective view of my improvement detached from the saw.

Referring to the accompanying drawings, the numeral 10 is used to indicate the saw-blade. The frame is constructed in the ordinary way with a handle portion 12 and a turnbuckle 13.

14 indicates a brace interposed between the bars 15 and 16 of the frame and parallel with the blade 10. One end of the brace 14 is tenoned in the bar 16 about midway between the blade and the turnbuckle.

17 indicates a brace, one end of which is tenoned in the bar 16 in proximity to the upper end thereof, and the opposite end is connected to the end of the brace 14 at the central portion of the bar 15.

45

18 indicates a hinge, one flap of which is interposed between the meeting ends of the braces 14 and 17, and said braces and hinge are connected by means of rivets or bolts 19, and the opposite flap of said hinge is fixed to the bar 15 of the frame, thus forming a flexible connection between said bar and the braces 14 and 17. By this construction it can plainly be seen that the bar 15 will be much stronger than in the old construction, 55 where the braces 14 and 17 are tenoned in said bar 15. The tenon which is necessitated by the old construction weakens the bar 15 at this point. By means of the said brace 17 all motion between the braces and the bar 60 16 is prevented, and all of the movement incident to the tightening and loosening of the saw is had at the hinge 18, and hence a stronger and more durable saw is provided.

Having thus described the device, what I 65 claim as my invention, and desire to secure by Letters Patent of the United States therefor, is—

An improved bucksaw-frame, comprising a side bar 15, a side bar 16, a turnbuckle connecting said bars, braces 14 and 17, and a hinge one flap of which is interposed between and connected to the meeting ends of the said braces and the opposite flap of said hinge secured to the bar 15, substantially as set forth. 75

OMAR A. ROGERS.
